(57) CLAIM

The ornamental design for a jewelry item, as shown and described.

DESCRIPTION

FIG. 1 is a front perspective view of a jewelry item showing our new design with stippling to indicate contrast;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view of the jewelry item shown in FIG. 1; and,

FIG. 8 is a bottom perspective view of the jewelry item shown in FIG. 1.

The broken line depicting the hinge, pin, and portions of the jewelry item shows unclaimed subject matter.
